UNITED STATES PATENT OFFICE.

PETER ISREAL VENARD, OF DENVER, COLORADO.

VACUUM-LINING FOR BOX-CARS AND THE LIKE.

1,278,529.

Specification of Letters Patent. Patented Sept. 10, 1918.

Application filed July 8, 1918. Serial No. 243,829.

To all whom it may concern:

Be it known that I, PETER I. VENARD, a citizen of the United States, residing at Denver, in the county of Denver and State 5 of Colorado, have invented certain new and useful Improvements in Vacuum-Linings for Box-Cars and the like; and I do declare the following to be a full, clear, and exact description of the invention, such as will enable others skilled in the art to which it 10 pertains to make and use the same.

My invention has for its object to provide a simply constructed vacuum lining which may be easily applied to all classes of closed 15 cars, storage rooms and the like without the necessity of altering them in any manner whatsoever, the provision of the lining serving to exclude both heat in summer and cold in winter, thus making it only necessary to 20 warm or chill the interior of the car or the like by the use of air currents, instead of using a great amount of ice or fuel.

With the foregoing object in view, the invention resides in the novel features of construction and arrangements of parts herein-after fully described and claimed, the descriptive matter being supplemented by the accompanying drawings which form a part 25 of this specification and in which:

30 Figure 1 is a central longitudinal section of a box car equipped with the improved vacuum lining;

Fig. 2 is a horizontal section on the plane indicated by the line 2—2 of Fig. 1;

35 Fig. 3 is a vertical transverse section on the plane of the line 3—3 of Fig. 1;

Fig. 4 is a top plan view partly in section showing one of the floor sections of the lining;

40 Fig. 5 is a longitudinal section on the plane indicated by the line 5—5 of Fig. 4;

Fig. 6 is a side elevation of one of the side sections, partly in section;

45 Fig. 7 is a sectional perspective view on the plane indicated by the line 7—7 of Fig. 6;

Fig. 8 is an edge view of one of the side sections;

50 Fig. 9 is a sectional perspective view of one of the top sections;

Fig. 10 is a top plan view of one of the floor sections which are employed at the ends of the floor; and

55 Fig. 11 is a sectional view on the plane indicated by the line 11—11 of Fig. 10.

In the drawings above briefly described, C designates a box car having the usual ends E, sides S floor F and a roof R, said sides S each having a door opening O provided with a suitable door D. I have shown my 60 invention applied to a box car for illustrative purposes, but I wish it understood that it is equally well applicable for refrigerator and insulated cars, also storage rooms and the like in which perishable goods are 65 kept.

A floor lining is provided consisting of a plurality of rectangular sections 1 which are disposed edge to edge and provided at the edges of the floor F with channels 2 opening upwardly (see Figs. 1, 2, 3, 4, and 5). As detailed more particularly in Figs. 4 and 5, each section 1 is of hollow formation, being formed of a pair of metal plates 3 suitably sealed at their edges and spaced apart 70 by blocks 4 of wood or the like, said blocks being held in place by studs 5 extending from one or both of the plates 3 and received in sockets 6 formed in the blocks. At the ends of the sections 1, the metal is suitably 75 bent to form the channels 2.

Positioned against the sides S of the car C and located at opposite sides of the door openings O, are side linings formed of vertically disposed rectangular sections 7 disposed edge to edge with their lower ends received snugly in the grooves 2 as featured most clearly in Figs. 1 and 3, the lower ends of said sections 7 being by preference slightly reduced in thickness as shown at 8. Like 80 the floor sections 1, the side sections 7 are formed of spaced plates 3^a held in spaced relation by blocks 4^a which are retained in place by studs 5^a. The metal at the upper edge of the sections 7 is bent to provide said 85 ends with channels 9 facing inwardly as detailed in Figs. 6, 7 and 8, but shown also in Fig. 3. As illustrated for instance in Fig. 2, the endmost of the sections 7 are shown abutting end linings formed of similar sections 100 7^a disposed against the inner sides of the car ends E and thus the outermost of the sections 7^a are retained in place. Preferably, the metal on the outer edge of the outermost sections 7^a is extended to provide a channel 105 to receive the endmost edge of sections 7, thus providing greater stability. In the drawings I have shown sections 7^a as identical in construction with sections 7, with this exception, said sections 7^a being provided on 110

their upper ends with channels 9^a as seen in Fig. 1.

To secure the side sections 7 in place at opposite sides of the door openings O, horizontally elongated key sections 10 are located at the upper ends of said openings and secured in place by screws or the like 11, said key sections also serving to prevent removal of the several ceiling sections yet to be described. The inner sides of the doors D are provided with linings 12 abutting the adjacent lining sections 7 and the key sections 10 as disclosed clearly in Figs. 1 and 2.

The ceiling lining, above referred to, consists of a plurality of rectangular sections 13 which, as detailed in Fig. 9, are formed of spaced apart metal plates 14, but the edges of these sections are not provided with channels such as those described in connection with the others. The outer edges of the endmost sections 13 are received snugly in the channels 9^a and the end sections 7^a abut the upper ends of said last named sections, being thus effectively secured in place, the lower ends thereof being held against displacement of the channels 2 of the endmost sections 1 of the floor lining. The sections 13 are disposed at opposite sides of the openings O and have their ends received in the channels 9 of the side sections 7 (see Fig. 3). By this arrangement, the sections 13 are not only supported by the sections 7, but they retain the upper ends of the latter in place, while the lower ends of said side sections 7 are maintained in proper position by the channels 2. In order to remove any of the sections 13, it is necessary to move them into a predetermined area, that is the area directly above the door openings O, whereupon they are free to move downwardly, provided the key sections 10 are first removed. To normally prevent movement of the ceiling sections 13 into the aforesaid area, one or more additional key sections 16 are provided, said sections normally occupying the area in question as shown in Fig. 1. The key sections 16 are supported and held in place by the key sections 10 above described, and the fastening means 11 employed for the latter, are the only fasteners necessary to retain the entire lining in the car.

In applying the lining, the floor sections 1 are first laid in place, after which the end 55 and side sections are applied, said end sections being in part held in place by said side sections as above described. The ceiling sections 13 are now slid from the area above the door openings O, along the channels 9, thus effectively retaining the upper ends of the side and end sections in place. The key sections 16 are now applied to retain the ceiling sections 13 in operative position, and when the other key sections 10 are now 65 secured in place by the screws or the like 11,

the entire lining is held in the car in the required manner. The door lining 12 may be secured to the doors D by any preferred means such as the screws 12^a illustrated in Fig. 1.

When the lining is used on certain types of cars, the endmost floor sections may be provided with removable portions 1^a to be removed when repairing the draft rigging.

From the foregoing, taken in connection with the accompanying drawings, it will be seen that I have provided a novel and very advantageous lining which may be secured in place within a room, box car or the like, by the provision of certain key sections 80 which alone must be anchored. A great saving is thus effected in nails, screws and the like, and removal of one or more sections at any time for repairs, is a simple matter, as is also the substitution of a new section 85 for one that has become damaged.

The several hollow sections of the lining by preference contain partial vacuums, since this is the most efficient insulator against both cold and heat, but I wish it understood 90 that if it is found desirable to pack said sections with insulating material this may well be done. In all cases, the lining will serve to exclude either hot or cold temperatures to advantage. It is thus unnecessary 95 to provide refrigerating or heating systems for cars which are to carry perishable goods in winter or summer, since after the interior of the car is either chilled or heated before being started on its route, the temperature 100 will remain substantially the same.

Since probably the best results are obtained from the several features shown and described, they are by preference followed, but within the scope of the invention as 105 claimed, numerous minor changes may well be made.

I claim:

1. A lining for box cars and the like including a plurality of sections disposed edge to edge and slidably into a predetermined area for removal, and one or more removable key sections occupying said area and preventing removal of said plurality of sections under normal conditions.

2. In combination with a box car or the like having a door or other opening in one side; a ceiling lining formed of abutting sections slidable horizontally into a predetermined area for removal, one or more key sections filling said area and preventing removal of said first named sections, a side lining formed of abutting sections slidably supporting said ceiling sections and disposed on opposite sides of said opening, 125 an additional key section at the upper end of said opening abutting the side sections at opposite sides thereof to retain them in place, said additional key section underlying said first named key section or sections 130

to retain the latter in position, and means for securing said additional key section removably in operative position.

3. In combination with a box car or the like having a door or other opening in one side; a ceiling lining formed of abutting sections slidable horizontally into a predetermined area for removal, one or more key sections filling said area and preventing removal of said first named sections, an end lining whose upper end is held in place by said ceiling lining, a side lining slidably supporting said ceiling sections and abutting said end lining to assist in holding the latter in place, said side lining being formed of sections disposed at opposite sides of said opening, an additional key section at the upper end of said opening and abutting the side sections at opposite sides thereof to retain them in place, said additional key section underlying said first named key section or sections to hold them in position, and means for securing said additional key section in place.
4. In combination with a box car or the like having a door or other opening in one side; a ceiling lining formed of abutting sections slidable horizontally into a predetermined area for removal, one or more key sections filling said area and preventing removal of said first named sections, an end lining, a side lining slidably supporting said ceiling sections and abutting said end lining to hold the latter in place, said side lining being formed of sections disposed at opposite sides of said opening, an additional key section at the upper end of said opening and abutting the side sections at opposite sides thereof to retain them in place, said additional key section underlying said first named key section or sections to hold them in position, and means for securing said additional key section in place.
5. In combination with a box car or the like having a door or other opening in one side; a ceiling lining formed of abutting
- sections slidable horizontally into a predetermined area for removal, one or more key sections filling said area and preventing removal of said first named sections, an end lining whose upper end is held in place by said ceiling lining, a side lining slidably supporting said ceiling sections and formed of sections disposed at opposite sides of said opening, an additional key section at the upper end of said opening and abutting the side sections at opposite sides thereof to retain them in place, said additional key section underlying said first named key section or sections to hold them in position, and means for securing said additional key section in place.
6. A structure as specified in claim 2, the upper edges of said side sections having channels in which the edges of the ceiling sections are received.
7. A structure as specified in claim 5, the upper edges of said end and side linings having channels in which the edges of said ceiling lining are received.
8. A structure as specified in claim 2, together with a sectional floor lining having a channel along its edge in which the lower edge of said side lining is received.
9. A lining for box cars or the like comprising a sectional floor lining having channels along its edges, sectional side and end linings whose lower edges rest in said channels, the upper edges of said side and end linings having channels, and a ceiling lining whose edges are received in said last named channels.
10. A vacuum lining for cars and the like formed of spaced parallel plates secured together at their edges, spacing blocks between said plates, said blocks having sockets, and studs extending from one of said plates into said sockets to retain said blocks in place.

In testimony whereof I have hereunto set my hand.

PETER ISREAL VENARD.
